WILL H. CLAPP, OF PASADENA, CALIFORNIA.

METHOD OF AND APPARATUS FOR PUMPING AN OIL WELL.

Application filed October 31, 1925. Serial No. 66,111.

My invention relates to the oil producing industry, and it relates in particular to oil well pumping equipment.

A common form of pumping equipment used for taking oil from the ground has a pump barrel which is placed near the bottom of a well and which is attached to the lower end of a pump tubing. The pump tubing extends into the well from the surface of the ground. Adapted to reciprocate in the pump barrel is a pump plunger which is attached to the lower end of a string of sucker rods. The string of sucker rods extends through the pump tubing and a stuffing box secured at the upper end of the pump tubing, and is connected to one end of a walking beam pivoted on a Samson post which is placed on the floor of the derrick of the well. The walking beam is oscillated by a walking beam crank which is secured to the shaft of a band wheel, the walking beam crank being connected to the end of a walking beam opposite to the string of sucker rods by means of a pitman. When the walking beam is in operation the pump plunger is reciprocated (through the inter-connecting mechanism), thus pumping oil to the surface of the ground through the pump tubing.

One of the foremost deficiencies in this type of pumping equipment is the breakage of the string of sucker rods. This type of breakage of the string of sucker rods, subjected to variable stresses, is what is known as "fatigue failure" or "progressive fracture" which occurs as follows: Under the stresses of a varying load some part of the rod where there is a local weakness (as a kink or a scratch on the metal surface which brings about a localized stress of high intensity) will start to fail. This failure will consist in a fracture of one of the minute crystals of the metal along one of its cleavage planes. This fracture sets up a stress of high intensity in an adjacent crystal which in turn will fail, and so on until the metal severs at this place.

It has been demonstrated that this character of failure is greatly effected in three different manners by the stresses placed on the string of sucker rods; first, it depends upon the maximum stress, the higher the maximum stress the sooner the break will take place; second, it is a function of the

range of stress, the greater the difference between the maximum and minimum stresses, the sooner the failure will occur; third, it is dependent upon the abruptness with which the load is given to and taken from the sucker rod string. It is demonstrable that a load instantly applied will produce twice as great a stress as though it had been applied gradually. Of course, failure also depends on repetition of variable loading.

The forces which make up the variable load on the upper end of the string of sucker rods consist of (1) the weight of the sucker rods and the plunger mechanism, (2) the weight of the column of oil being lifted, (3) frictional resistances, and (4) inertia forces whose value depends on the weight being lifted and the character of the motion of the pump plunger and string of sucker rods. There is only one of these four forces which can be modified to obtain more ideal stress conditions, and this is the inertia force whose value can be changed by modifying the character of the motion of the string of sucker rods and pump plunger.

The motion of the string of sucker rods and pump plunger in an ordinary crank mechanism is identical in character with that of an engine cross head in which the strokes are the same in length and number per minute, and in which the ratio of the connecting rod length to the crank length is the same as the ratio of the pitman length to the walking beam crank length. The pump, therefore, starts its stroke at zero velocity, accelerates to maximum at the middle of the stroke and decelerates again to zero at the end of the stroke. Since the inertia force varies directly proportionally to acceleration, then the inertia force of such a motion of the pump will cause a high maximum load, a large range of maximum and minimum loads and it also will have a somewhat abrupt change in load.

It is an object of this invention to provide an apparatus for operating the plunger of a reciprocating pump of the character mentioned in such a manner that the maximum stress placed on the sucker rods will be lower and the range of maximum and minimum loads will be less than in the ordinary pumping equipment.

It is another object of this invention to provide an apparatus of this character in

which there will be no abrupt change in loads placed on the string of sucker rods.

It is a further object of this invention to provide an operating apparatus of this character having a piston which is connected directly to the walking beam.

It is also an object of this invention to provide a pump operating apparatus in which the piston is operated by compressed air which is admitted during a greater part of its down stroke. The piston is accelerated while the air is admitted and decelerates while air expands after the supply of air to the cylinder has been discontinued.

It is a further object of my invention to provide a pump operating apparatus of this character in which the piston is allowed to rise by releasing air from the cylinder.

It is a still further object of this invention to provide a pump operating apparatus in which the piston compresses the air in the cylinder during the later portion of its up stroke, being thereby gradually decelerated.

It is an additional object of this invention to provide a pump operating apparatus in which compressed air may be admitted to the cylinder as the piston nears the upper end of the stroke, thereby completing the gradual deceleration of the piston to zero velocity and then reversing its direction of motion.

It is a further object of the invention to provide a pump operating apparatus of this character in which the admittance to and the exit of air from the cylinder is controlled by a slide valve, which slide valve is operated by means associated with the piston.

It is another object of this invention to provide a pump operating means of the character mentioned in which a means for operating the slide valve is adjustable so that satisfactory periods of acceleration and deceleration of the piston may be acquired, so that the plunger of the pump being operated may have a desired motion.

It is a still further object of this invention to provide a pump operating mechanism which will have a high mechanical efficiency as compared with the ordinary drive.

An additional object of this invention is to provide a pump operating apparatus which will be comparatively cheap to operate.

It is an additional object of the invention to provide a pump operating mechanism of the character mentioned having a piston of variable stroke and speed under direct control of the operator, the length of the stroke being governed by the cut-off and the speed by the adjustment of the pressure regulating valve.

It is a still further object of the invention to provide a pump operating mechanism of the character mentioned from which an

indicator card may be made which will inform the operator of certain conditions in the well.

Other objects and advantages of this invention will be made evident hereinafter.

Referring to the six drawings in which I illustrate a preferred form of my invention:

Fig. 1 is a diagrammatic view illustrating all of the parts of my invention and illustrating the utility thereof.

Fig. 2 is an elevational view of a pump operating mechanism of my invention.

Fig. 3 is an elevational sectional view taken as indicated by the line 3—3 of Fig. 2.

Fig. 4 is a section taken as indicated by the line 4—4 of Fig. 3.

Fig. 5 is a partial plan view of Fig. 3.

Fig. 6 is a section taken on the line 6—6 of Fig. 3.

Fig. 7 is an enlarged sectioned detail showing clearly the slide valve arrangement and operating mechanism therefor, which comprises an important part of my invention.

Fig. 8 is a section of the valve and its control mechanism taken substantially at right angles to Fig. 7.

Fig. 9 is a diagrammatic view illustrating the positions of the various parts of my invention at the start of the down stroke.

Fig. 10 is a diagram illustrating the positions of the parts at the end of the maximum acceleration of the down stroke of the pump operating mechanism.

Fig. 11 shows the positions of the parts at the bottom of the down stroke.

Fig. 12 shows the positions of the parts at the end of the acceleration of the up stroke of the mechanism.

Fig. 13 shows the positions of the parts near the end of the up stroke.

Figs. 14, 15, 16 and 17 are graphic diagrams illustrating the results of my invention as compared with present pumping equipment.

The essential parts of the pump operating mechanism of my invention are shown in Figs. 2 to 8 inclusive. With reference particularly to these figures, my invention provides a base 20 which is supported on a foundation 21. The base 20 consists of a lower casting 22 to which a vertical housing 23 is secured. The housing 23 has an upper casting 24 secured thereto. The casting 24 has a central cylindrical opening 25 through which a lower extending lip 27 of the cylindrical casting 28 extends. The cylindrical casting 28 is secured to the upper casting 24 of the base 20 by means of bolts 29 which are secured to the casting 24 and extend through a flange 30 provided by the cylindrical casting 28. The cylindrical casting 28 provides a cylinder 32 and a valve chamber 33 which is positioned directly

adjacent to the upper end of the cylinder 32. The upper end of the casting 28 has a cap 34 secured thereto by suitable bolts 35, this cap 34 closing the upper end of the cylinder 32 and the valve chamber 33.

Adapted to reciprocate vertically in the cylinder 32 is a piston 38. A piston rod in the form of a tubular member 39 is secured to a lower face of the piston 38 by a flange 40, this flange 40 being secured in place by cap screws 41. A cross head 43 placed inside the base 20 is secured to the lower end of the piston rod 39 by means of a lower flange 44. The cross head 43 has arms 46 in which bearings 47 are provided through which vertical guides 48 extend. The lower ends of the vertical guides 48 are rigidly secured in the foundation 21. The upper ends of the guides 48 extend through projections 49 formed at the lower end of the cylinder casting 28 and have nuts 50 secured to the upper end thereof. Rubber bumpers 51 are provided around the guides 48 just below the upper casting 24, against which upper faces of the bearings 47 may strike in event that the piston 38 should move above its normal stroke. Similar rubber bumpers 52 are provided around the guides 48 just above the base casting 22, against which lower faces of the bearing portions 47 of the crosshead 43 may strike in event that the piston 38 should move below its normal stroke.

Bearing pins 53 are secured to the outer ends of the arms 46, these bearing pins having lower ends 54 of vertical reins 55 pivoted thereon. These reins 55 extend upward and outward from the base 20 through openings 56 formed in the upper casting 24. The upper ends of the reins 55 are secured by nuts 58 to a suitable construction 59, by means of which the reins may be connected to a walking beam 60 of a derrick equipment. The construction 59 may be provided with vertical arms 61 which are secured to a shaft 61^a which is supported at one end of the walking beam 60.

As clearly shown in Figs. 3, 7 and 8, a sleeve 62 is secured in the upper portion of the valve chamber 33. Openings 63 through this sleeve 62 connect the interior thereof with the passage 64 and the port 65 in the upper end of the cylinder 32. A slide valve 66 is adapted to operate in the valve chamber 33. This slide valve 66 is provided in the form of a shell 67 having upper and lower ends 68 which are adapted to contact the walls 62^a and 33^a of the sleeve 62 and of the chamber 33, respectively, which ends 68 are connected by a neck 69 which is of smaller diameter than the portions 68. The shell 67 is supported by arms 70 which extend inward to hubs 71. This arrangement provides a passage 72 which extends entirely through the slide valve 66. The hubs

71 are secured by nuts 74 on a valve rod 73 which extends through the chamber 33. The valve rod 73 extends downward from the valve chamber 33 through a stuffing box 74. The lower end of the valve rod 73 is provided with a block 75 having a pair of lower shoulders 76 and a pair of upper shoulders 77 as shown in Fig. 7. A pair of vertically extending tappet rods 80 are secured to an arm 81 of the cross head 43. These tappet rods 80 extend through openings 82 formed in the upper casting 24 and they extend adjacent to and at each side of the valve rod 73. Adjustably secured to the tappet rods 80 are a pair of lower or deceleration tappets 84 and a pair of upper or up stroke tappets 85. These lower and upper tappets 84 and 85 are adjustably secured to the tappet rods 80 so that certain adjustments in the operation of the apparatus may be made. This, however, will be described later.

Secured to an upper face of the upper casting 24 is a bracket 87 which supports pins 88 on which dogs 89 are pivotally secured. These dogs 89, as shown in Fig. 7, are substantially the reverse of S shape. The upper ends 90 of the dogs 89 are positioned so that they are capable of engaging the lower and upper shoulders 76 and 77 of the block 75. The lower arms 91 are positioned so that they may be engaged by inner faces 92 and 93 of the lower and upper tappets 84 and 85, respectively.

Compressed air is supplied to the central part of the valve chamber 33 surrounding the neck 69 of the valve 66 by means of a pipe 95, and air is taken from the valve chamber 33 near the lower part thereof by a pipe 96. The upper end of the valve rod 73 extends through an opening 98 formed at the upper end of the valve chamber 33 and has a lift plunger 99 attached thereto. This lift plunger 99 operates in a cylinder 100 provided by a member 101 which is secured to the cap 34 by suitable cap screws 102.

A hole 106 is formed through the wall of the member 101 at a point opposite the position occupied by the lower end of the plunger 99 when the upper end 68 of the valve 66 covers and closes the openings 63. A small hole 107 through the wall of the member 101 communicates the lower end of the cylinder 100 with the atmosphere. The valve rod 73 has a sleeve 104 secured thereto by a nut 105 at the place where it extends through the opening 98 at the upper end of the valve chamber 33. A pipe 108 is connected to the valve chamber 33 adjacent to the air inlet 95. A branch 109 of this pipe 108 connects with the upper part of the opening 98. The branch 109 is provided with a valve 112 having a lever 113 which is adapted to be engaged and oper-

- ated by a lift tappet 115 which is secured near the upper part of one of the tappet rods 80. This lift tappet 115 is adapted to engage the lever 113 and open the valve 112 when it moves upward past the lever 113 and close the valve 112 when it moves downward past the lever 113. The operation of the valve is effective in supplying air to the cylinder 100 below the lift plunger 99.
- 10 The pipe 108 as shown in Fig. 3 connects with the upper end of the cylinder 32 through the cap 34. The pipe 108 has a valve 117 placed near the end which connects with the cylinder 32 which may be operated 15 to supply compressed air to the upper end of the cylinder 32 in case the piston has moved beyond its upper limit. This will be explained later.
- 10 The pump operating mechanism, just described, is connected to oil well equipment as shown in Fig. 1. The walking beam 60 is pivoted on the upper end of a Samson post 130 which is a part of standard equipment of a derrick 131. The end of the walking beam 60, opposite from that end to which the reins 55 are attached, has a polish rod 132 attached thereto. This polish rod 132 passes through a stuffing box 133 and extends into the upper end of a pump tubing 134. 25 The polish rod 132 has a string of sucker rods 135 connected thereto which extends downwardly through the pump tubing 134 to the plunger, not shown, of an oil well pump 136, placed at the bottom of a well 30 137. The inlet pipe 95 which supplies compressed air to the valve chamber 33 extends from a compressed air reservoir 139 which is supplied with compressed air by means of a compressor 141, the pipe 95 having a regulating valve 140. The compressor 141 is connected to the reservoir 139 by a pipe 142 having a relief valve 143. The compressor 40 141 is preferably operated by a gas driven engine or Diesel engine 144. The air outlet 45 96 extends to a low pressure air receiver 145, and the low pressure air receiver 145 is connected to the compressor 141 by means of a pipe 147.

50 The operation of my invention is substantially as follows:

In Figs. 2, 3, 7, 8 and 9 I show the position of the various parts of the pump operating mechanism at the beginning of the down stroke. The slide valve 66 is positioned (in these figures) so that the port 65 is in communication with the air inlet pipe 95. Compressed air passes through the pipe 95, the adjacent portion of the valve chamber 33 and through the port 65 into the upper end of the cylinder 32. The valve 66 is supported in this position by means of the dogs 89. These dogs 89 are at this time in engagement with the lower shoulders 76 of the block 75 which is secured at the lower 60 65 end of the valve rod 73. The compressed

air, being admitted to the upper end of the cylinder 32, forces the piston 38 and its associated parts downward until these parts occupy the positions as shown diagrammatically in Fig. 10. This motion of the piston 70 38 comprises the period of maximum acceleration of the down stroke thereof.

When the piston arrives at the position shown in Fig. 10, the lower valve tappets 84 secured to the rods 80 will have moved 75 into such positions as to engage the lower arms 91 of the dogs 89. The dogs 89 are swung by the lower tappet 84, causing the upper arms 90 of these dogs to disengage the lower shoulder 76 of the block 75. This 80 disengagement allows the slide valve 66 to move downward under force of gravity and the additional downward force due to the fact that the lower enlarged end 68 of the valve 66 is larger than the upper enlarged 85 end 68 thereof, so that the pressure in the space surrounding the neck 69 exerts an unbalanced downward force on the valve 66. As the tappets 84 move past the dogs 89, these dogs return to normal position in time 90 to engage the upper shoulder 77 of the block 75. The slide valve 66, when the dogs 89 are in engagement with the shoulder 77, is in such a position as to close the port 65 which connects between the valve chamber 33 and 95 the cylinder 32. The upper enlarged portion 68 of the valve shell 67 closes this port 65. This position of the valve stops the supply of air to the cylinder 32. The air which has already been supplied to the cylinder 32 100 will expand and the piston will move to the lower end of its downward stroke, this position being shown in Fig. 11. The movement of the piston during the expansion of the air in the cylinder 32 comprises the 105 period of maximum deceleration of the down stroke of the piston 38.

When the piston 38 has reached its lowermost position, the upper tappets 85 will have moved into such a position as to engage the lower arms 91 of the dogs 89 and to swing them out of engagement with the upper faces 77 of the block 75. This allows the block 75 to move downward so that the inner faces of the upper arms 90 of the dogs 110 89 will rest on faces 150 of the block 75. This disengagement of the dogs 89 permits the slide valve 66 to move into its lowermost position so that the upper end thereof is below the port 65. The port 65 is thus communicated with the air outlet pipe 96 by means of the passage 72 through the valve 66. As the air passes from the cylinder 32 115 the piston 38 will move upward.

From an inspection of Fig. 1, it will be 120 seen that during a down stroke of the piston 38 the plunger of the pump 136 is moving through its up stroke and that during an up stroke of the piston 38 the pump plunger 125 is moving through a down stroke. 130

Therefore the weight of the pump plunger 99 pulls upward on the piston 38 and causes it to move upward when the air outlet pipe 96 is connected with the upper end of the cylinder 32.

The piston, with its associated parts, moves upwardly until it reaches a position, as shown in Fig. 12. The tappets 84 and 85 may pass the dogs 89 since the arms 90 thereof engage the faces 150 of the block 75 and hold the dogs 89 in retracted positions.

When the piston reaches the position shown in Fig. 12, the tappet 115 on the upper end of the tappet rod 80 engages the valve lever 113 and swings it to open the valve 112. High pressure air immediately flows through the pipe 109 into the opening 98 and the cylinder 100. The pressure thus built up in the cylinder 100 raises the plunger 99 and the associated valve parts, as shown in Fig. 12. As soon as the upper end 68 of the valve 66 has closed the openings 63 connecting with the port 65, the upper end of the sleeve 104 moves past the pipe 109 and cuts off the supply of air to the cylinder 100. The compressed air in the cylinder 100 expands, forcing the plunger 99 further upward until the lower edge thereof uncovers the hole 106 and releases the air to atmosphere. At this point the upper shoulders 77 of the block 75 are in a position slightly above the ends of the arms 90 of the dogs 89 so that the latter move into position below these shoulders 77. The air in the cylinder escapes through the hole 106 and the small hole 107 to atmosphere, reducing the upward pressure on the plunger 99 and permitting the valve to settle until the shoulders 77 rest on the dogs 89, as shown in Fig. 10. In this position the upper end 68 of the valve 66 cuts off the cylinder 32 from the valve chamber 33, so that, as the piston 38 continues its upward movement, the air in the cylinder 32 is compressed and resists with increasing force the motion of the piston 38, gradually decelerating it.

As the piston 38 approaches the end of the up stroke, a dash pot 156 mounted on the arm 81 of the cross head 43 engages the lower end of the valve rod 73 and raises it and the valve 66, as shown in Fig. 13, admitting high pressure air from the valve chamber to the cylinder 32 above the piston 38. This high pressure acting upon the piston 38 completes the gradual deceleration to zero and reversal in direction thereof, as indicated in Fig. 9.

As the piston 38 reaches the end of the up stroke the dash pot 156 carries the valve rod 73 upward to a position in which the shoulders 76 of the block 75 are slightly above the ends of the arms 90 of the dogs 89, so that the latter drop into position be-

neath the shoulders 76. When the piston reverses direction and starts on its down stroke the dash pot 156 ceases to support the valve rod 73, with the result that the valve assembly moves downward until the shoulders 76 rest on the dogs 89, as shown in Figs. 2, 3, 7, 8 and 9. In this position the apparatus is in position to start anew the cycle just described.

By making the lower tappets 84 adjustable it is possible to change the time at which the valve 66 will close the port 65 and thus change the period of acceleration of the downstroke of the piston 38. By making the upper tappets 85 adjustable in position it is possible to vary the time at which the air is exhausted from the cylinder 32, thus changing the position at which the piston starts on its up stroke. In this manner the length of stroke of the pump may be changed. Likewise, the position of the tappet 115 may be changed in order to change the time at which the port 65 is again closed and the compression begins to decelerate the piston. The relation of the dash pot 156 and valve rod 73 is not adjustable; in service it will generally be most desirable to set the tappet 115 so that the compression will begin at such a point in the stroke that the pressure at the end of the stroke will be substantially equal to the admission pressure. This is advantageous from the standpoint of greater thermal efficiency and gradual change of decelerative force, and reduces the function of the dash pot 156 to opening the valve to admission at the end of the stroke.

If, however, through improper adjustment of the lift tappet 115 or failure of the lift plunger 99 to function properly, the port 65 should not be closed soon enough for a compression to be built up to a sufficient magnitude to stop the piston 38 at its normal uppermost position, the dash pot 156 will lift the valve 66 and open the port 65 to admission pressure. This permits the cylinder 32 above the piston 38 to fill with air at admission pressure, providing a large but not violently applied decelerating force. This force may be sufficient to stop the piston 38 before it reaches the port 65; if not, the piston 38 may cover and close the latter. In this case, further movement of the piston 38 rapidly increases the compression to such a point that it is quickly brought to rest. Thus, in this extreme case, the dash pot 156 serves as an emergency means for opening the port 65 to provide a cushion of high pressure air, during the further compressing of which the piston 38 is stopped.

Sometimes, during preliminary adjustments of the mechanism, the piston 38 will overrun the port 65 as outlined in the previous paragraph. In any case, when the pis-

ton 38 is at rest in a position above the port 65, it is only necessary to operate the valve 117 to supply air to the extreme upper end of the cylinder 32 so that the piston 38 may 5 be returned and the port 65 opened.

In order to have a clear understanding of the advantages of my invention it is necessary to clearly comprehend the character of the results achieved by modifying the motion 10 of the plunger from the motion produced by the ordinary crank and pitman arrangement. It is also necessary to understand the character of the results of the plunger with the crank and pitman arrangement 15 and the character of the results of the plunger when it is operated by my invention. The steps taken to arrive at the motion produced by my invention should also be understood. For this purpose and for the purpose 20 of comparing the results of my invention with results of present equipment, recourse is had to Figs. 14 to 17 of the drawings.

Let us first consider the ordinary crank and pitman arrangement. In Figs. 14, 15 25 and 16 I show curves illustrating how the forces on the upper end of the string of sucker rods vary during the up and down stroke of the pump. There are four forces which make up the resultant force P which 30 stresses the rod at any instant. These forces are W_r which is the weight of the sucker rod and plunger mechanism, W_o which is the weight of the column of oil that has been lifted, F_1 and F_2 which are frictional resistances 35 on the up stroke or down stroke, respectively, and I which is the inertia force whose value depends upon the weight being lifted and the character of the motion of the plunger.

40 In the diagram of Fig. 16, P_1 represents the force acting upon the upper end of the sucker rod when the pump begins its up stroke, P_2 represents the force at the end of the up stroke, P_3 represents the force at the 45 beginning of the down stroke and P_4 represents the force at the time of the down stroke. P represents the force acting upon the upper sucker rod at any position of the stroke. Under the stresses produced by the 50 variable force, P , which in this case varies from a maximum of 10,210 pounds plus frictional resistances to a minimum of 2,690 pounds minus the frictional resistances, with an abrupt change in the load at the end of each stroke, the stresses on the sucker rods 55 which tend to produce fracture thereof are very large.

Next, let us refer to Fig. 17 which is a 60 step in arriving at the form of motion of my invention. Since it is possible only to alter the inertia force by a modification of motion in the plunger it will be seen that P_1 can be reduced in the same amount that it is possible to reduce I . The inertia force I varies 65 directly with the acceleration and in fact

the curve of inertia force may represent a curve of acceleration of W_r and W_o if drawn to a proper scale. It is apparent that if a weight is to be raised through a distance S , Fig. 16, in a given time T the acceleration 70

will be least when it is maintained at a constant amount throughout the interval, but in this case the body would not be brought to rest but would be traveling at its highest speed at the end of the stroke. If the acceleration 75

is maintained constant to mid-stroke an equal deceleration will be required to bring the body to rest. In Fig. 17 I show a diagram of forces acting on the rod when the accelerating force is carried somewhat 80

beyond mid-stroke. The same weights and time of raising are assumed as in Fig. 16. By carrying the acceleration beyond mid-stroke the inertia force I_1 is reduced materially while I_2 is increased in amount. Thus 85

it will be seen that the maximum stress on the rod may be reduced and the range between the maximum and minimum stress of the rod may also be reduced. If the return 90

stroke is made in the same time and in the same manner we see that I_3 bears the same relation to I_1 as the weight W_r being lowered does to the weights W_r and W_o being raised which, for the particular case we are 95

considering makes I_3 equal to 4/7 of I_1 . Similarly, I_4 equals 4/7 of I_2 . The result of this 100

change in character of motion is to decrease both the maximum load P_1 and the range of load $P_1 - P_3$, and it will be apparent that this improvement will be further promoted by using a still smaller acceleration on the up stroke and continuing it for a longer portion S_1 of the stroke, carrying this out until the final force P_2 becomes equal to P_3 . To go further is to make P_2 less than P_3 and 105

this will increase the range of stress due to the difference between maximum and minimum loads.

It is still possible to make one further improvement by taking a longer period of time for the up stroke of the piston 38 than for the down stroke thereof. This will decrease P_1 still further but at the expense of P_3 but, if one also continues to keep P_2 equal to P_3 115 by still further increasing the ratio of S_1/S_2 (equals S_3/S_4), the effect is to increase P_4 as P_1 decreases. Such increase can be carried out advantageously until P_4 equals P_1 . Now, these are the relationships which 120 should exist in order to have the least maximum load and the least range of load on the sucker rod, viz., P_1 equals P_4 and P_2 equals P_3 .

A curve in which P_1 equals P_4 and P_2 equals P_3 is shown at C in Fig. 14. By assuming this curve C it will be seen that the load changes abruptly near each end of the stroke and it is known that abrupt changes of loading increase the liability to breakage 125 of sucker rods. A final modification of the 130

curve is brought about by increasing very slightly the actuating force and the added acceleration thus obtained permits the gradual change from a maximum to a minimum load such as shown by the curve B in Fig. 14. The data for these two curves shown in Figs. 14 to 17 inclusive, are taken from an example in which the stroke is six feet and the number of cycles 16-2/3 per minute, this time being taken for convenience of plotting the curves since one degree of band-wheel rotation is then equivalent to 1/100 of a second.

The curve indicated by B in Fig. 14 represents the motion which is produced by the apparatus of my invention. The periods of acceleration and deceleration may be very accurately arranged to agree with what is considered the most desirable motion of the pump plunger. Comparing the curve A of Fig. 14, which is for the ordinary crank and pitman, with the curve B, which is the motion produced by my invention, it will be seen that there is quite a reduction in maximum stress and quite a reduction in range of stresses, and that there is no abrupt change in loading on the sucker rod. The maximum load in curve A is 10,210 pounds, whereas the maximum load of the curve B of my invention is only 8,127 pounds. The maximum range of load for curve A is 7,520 pounds, whereas for curve B of my invention it is only 5,144 pounds. The stroke of the maximum load of my invention covers substantially seven-tenths of the time period of the up stroke as illustrated by the curve B of Fig. 14. The stroke of minimum load, also shown by curve B, covers substantially the same portion of the time period of the down stroke. The curve B of Fig. 14 may be replotted to co-ordinates of force and displacement instead of force and time and the results will be as shown by the curve of Fig. 15 which is nothing more or less than an ordinary engine indicator card with a late cut-off. In other words, if an engine were designed to operate without a fly-wheel and with a variable stroke and were to be attached directly to the beam, as shown in Fig. 1, it would automatically bring about a motion of the rods which would be similar to that of this analysis. In the curve of Fig. 15 the expansion is not like that of an engine since the object of the curve is simply to bring about a gradual change of load. The manner in which this change occurs is not material. An indicator card in the form of Fig. 15 taken from the engine in actual service would be useful in determining the pumping conditions and the friction in the well.

I claim as my invention:

1. A method of operating a plunger of an oil well pump through a string of sucker rods in order to reduce the maximum stress set up in the sucker rods and to reduce the

range of stresses set up in the sucker rods, said method comprising: accelerating said sucker rods during the greater part of the up stroke thereof, thus causing the maximum tensile stress set up in said sucker rods 70 to be of relatively low value; decelerating said sucker rods during the lesser part of said up stroke; accelerating said sucker rods during the greater part of the down stroke thereof thus causing the minimum stress set 75 up in said sucker rods to be of relatively high value; and decelerating said plunger during the lesser part of said down stroke.

2. A method of operating a plunger of an oil well pump through a string of sucker rods in order to reduce the maximum stress set up in the sucker rods and to reduce the range of stresses set up in the sucker rods, said method comprising: accelerating said sucker rods substantially uniformly during 80 substantially seven-tenths of the time of the up stroke thereof, thus causing the maximum tensile stress set up in said sucker rods to be of relatively low value; decelerating said sucker rods during the lesser part of said 85 up stroke; accelerating said sucker rods substantially uniformly during substantially seven-tenths of the time of the down stroke thereof thus causing the minimum stress set up in said sucker rods to be of relatively 90 high value; and decelerating said plunger during the lesser part of said down stroke.

3. A method of operating a plunger of an oil well pump through a string of sucker rods in order to reduce the maximum stress 100 set up in the sucker rods and to reduce the range of stresses set up in the sucker rods, said method comprising: accelerating said sucker rods during the greater part of the up stroke thereof, thus causing the maximum 105 tensile stress set up in said sucker rods to be of relatively low value; decelerating said sucker rods during the lesser part of said up stroke at a rate which will reduce the stress until at the end of the up stroke, it 110 substantially equals the minimum stress set up in said sucker rods; accelerating said sucker rods during the greater part of the down stroke thereof thus causing the minimum stress set up in said sucker rods to be 115 of relatively high value; and decelerating said plunger during the lesser part of said down stroke at a rate which will increase the stress until, at the end of the down stroke, it substantially equals the maximum stress 120 set up in said sucker rods.

4. A method of operating a plunger of an oil well pump through a string of sucker rods in order to reduce the maximum stress set up in the sucker rods and to reduce the 125 range of stresses set up in the sucker rods, said method comprising: accelerating said sucker rods substantially uniformly during substantially seven-tenths of the time of the up stroke thereof, thus causing the maximum 130

tensile stress set up in said sucker rods to be of relatively low value; decelerating said sucker rods during the lesser part of said up stroke at a rate which will reduce the 5 stress until at the end of the up stroke, it substantially equals the minimum stress set up in said sucker rods; accelerating said sucker rods substantially uniformly during substantially seven-tenths of the time of the 10 down stroke thereof thus causing the minimum stress set up in said sucker rods to be of relatively high value; and decelerating said plunger during the lesser part of said down stroke at a rate which will increase 15 the stress until, at the end of the down stroke, it substantially equals the maximum stress set up in said sucker rods.

5. A method of operating a plunger of an oil well pump through a string of sucker rods in order to reduce the maximum stress set up in the sucker rods and to reduce the range of stresses set up in the sucker rods, said method comprising: accelerating said sucker rods during the greater part of the 20 up stroke thereof, thus causing the maximum tensile stress set up in said sucker rods to be of relatively low value; decelerating said sucker rods during the lesser part of said up stroke at a rate which will reduce 25 the stress until, at the end of the upstroke, it substantially equals the stress desired to be set up in the initial portion of the down stroke; accelerating said sucker rods during the greater part of the down stroke thereof 30 thus causing the minimum stress set up in said sucker rods to be of relatively high value; and decelerating said plunger during the lesser part of said down stroke at a rate which will increase the stress until, at the 35 end of the down stroke, it substantially equals the stress desired to be set up in said sucker rods in the initial portion of the up stroke.

6. An apparatus of the class described 40 comprising: a plunger adapted to reciprocate in a barrel; a string of sucker rods connected to said plunger; a walking beam connected to said string of sucker rods; a piston connected to said walking beam, said 45 piston adapted to reciprocate in a cylinder; a valve adapted to control the admission of and emission of a gas from said cylinder; means for positioning said valve to admit gas to said cylinder for forcing said piston 50 downward; means for positioning said valve to shut off said gas, said gas in said cylinder expanding to move said piston to the lower 55

end of its down stroke; means for positioning said valve to emit gas from said cylinder to permit said piston to rise in said cylinder; and means for positioning said valve to prevent further emission of gas. 60

7. An apparatus of the class described comprising: a plunger adapted to reciprocate in a barrel; a string of sucker rods connected to said plunger; a walking beam connected to said string of sucker rods; a piston connected to said walking beam, said piston adapted to reciprocate in a cylinder; a valve adapted to control the admission of and emission of a gas from said cylinder; means for positioning said valve to admit gas to said cylinder for forcing said piston 70 downward; means for positioning said valve to shut off said gas, said gas in said cylinder expanding to move said piston to the lower end of its down stroke; means for positioning said valve to emit gas from said cylinder to permit said piston to rise in said cylinder; and means for positioning said valve to prevent further emission of gas, said last named means adapted to operate before said piston reaches the upper 75 end of its stroke so that said piston will be decelerated. 80

8. A method as set forth in claim 1 in which the up stroke is given more time than the down stroke. 85

9. An apparatus of the class described comprising: a plunger adapted to reciprocate in a barrel; a string of sucker rods connected to said plunger; a piston operatively connected with said string of sucker rods; a cylinder in which said piston is adapted to slide, there being a closed expansion chamber formed in said cylinder by said piston so that fluid admitted thereto under pressure tends to raise said sucker rods; valve means controlling an inlet into said chamber and an outlet from said chamber; a high pressure tank connected to said inlet; a low pressure tank connected to said outlet; and a compressor adapted to draw fluid from said low pressure tank and force it into said high pressure tank, the circuit 95 of fluid between said chamber, said low pressure tank, said compressor, and said high pressure tank being normally closed to the atmosphere. 100

In testimony whereof, I have hereunto set 110 my hand at Los Angeles, California, this 22nd day of October, 1925.

WILL H. CLAPP.
